UNITED STATES PATENT OFFICE.

CHARLES H. BELL, OF CLEVELAND HEIGHTS, OHIO, ASSIGNOR TO THE EATON AXLE & SPRING COMPANY, OF CLEVELAND, OHIO, A CORPORATION OF OHIO.

CLOSURE.

Application filed July 18, 1928. Serial No. 293,850.

This invention relates to improvements in closures, such as are used for closing the openings of radiators and fuel tanks of automobiles, etc. More particularly, the invention relates to improvements in closures of the bayonet joint type.

The general object of the present invention is the provision of a closure of the type described which is of simple and inexpensive construction and highly efficient in use.

Further objects of the invention are in part obvious and in part will appear more in detail hereinafter.

In the drawing, Fig. 1 is a plan view of a closure embodying my invention; Fig. 2 is a cross-sectional view thereof on the line 2—2, Fig. 4; Fig. 3 is a vertical sectional view of the closure detachably connected to a tubular neck surrounding the opening to be closed, the section through the closure being on the line 3—3, Fig. 1; Fig. 4 is a bottom plan view of the closure; Fig. 5 is a top plan view of the neck shown in Fig. 3; Fig. 6 is a vertical sectional view thereof on the line 6—6, Fig. 5; Fig. 7 is a top plan view of a portion of a modified form of closure; and Fig. 8 is a vertical sectional view on the line 8—8, Fig. 7.

In the present embodiment of the invention, 1 represents an automobile radiator, fuel tank or other object having an opening 2 to be closed, which opening is surrounded by a tubular neck to which the closure is adapted to be detachably secured by a bayonet joint connection. Said neck includes a cylindrical body portion 3 which may be an integral part of member 1 or separate therefrom and suitably secured thereto, the latter arrangement being here shown with the body portion provided with an outwardly extending, annular base flange 4 for welding or other suitable securing to member 1. At the upper end of the neck body portion 3 is an inwardly extending annular flange 5 which terminates in a depending flange 6. At two diametrically opposed points, parts of flanges 5 and 6 are cut away to provide two passage-ways 7 for the locking fingers of the closure, as will later appear. The cutting away of said flange parts provides two depending flange portions 6 of substantially semi-circular form and the two lower edges of these flange portions are inclined to provide two cam surfaces 8 with which the closure locking fingers are adapted to

cooperate in effecting a detachable locking connection of the closure to the neck. Preferably, a recess or dwell 9 is provided at the rear end of each cam surface to receive a closure locking finger, and adjacent each dwell each flange portion 6 is provided with a depending projection 10 to form stops for the closure locking fingers and thus limit rotary movement thereof relative to the neck, all as will appear hereinafter.

The closure of the present application includes a one-piece body member having a central dome portion 15 of non-circular shape, such as hexagonal, a marginal portion 16 of annular shape and a depending skirt portion 17 of cylindrical shape, said skirt portion being preferably but slightly larger in diameter than that of the neck body portion 3 with which it is adapted for telescopic relation. Slidably but non-rotatably arranged in the recess 18 formed by the dome portion 15 is the upper end portion of a locking member which is provided at its lower end with two diametrically opposed fingers adapted for locking engagement with the cam surfaces 8 of the neck.

The locking member here shown is of inverted, substantially cup shape and includes a hexagonal top portion 20 and a side wall portion 21 which is provided at its lower end with two depending diametrically opposed finger portions 22 which terminate in outwardly extending cam engaging portions 23. In cross dimension, the upper end portion of the locking member corresponds in size and shape with the recess 18. In other words, the upper end portion of the locking member is free to slide vertically in recess 18 but cannot turn therein due to the non-circular shape of the recess and said locking member portion. In the present embodiment of the invention, this recess and locking member portion are of hexagonal shape, but obviously, they could be of any non-circular shape, such as square or rectangular.

The locking member of the closure is maintained in assembled relation with the body member thereof by a depending connecting member passing through centrally disposed apertures in the top portion 20 of the locking member and the dome portion 15 of the body member.

In the construction shown in Fig. 3, this connecting member is in the form of a tube

25 having its upper and lower ends bent outwardly in the form of annular flanges 26 and 27 respectively, which prevent complete disassembly of the body and locking members.

5 Mounted upon the lower flange 27 of this connecting tube is a coiled spring 30 having its upper end engaging the top portion 20 of the locking member and normally maintaining said top portion in engagement with the 10 top wall of the dome portion 15 of the body member, as clearly shown in Fig. 2.

The closure is detachably secured to the neck by passing the locking finger portions 23 down through the passageways 7 of the 15 neck and then imparting clockwise rotary movement to the closure so as to cause said finger portions to ride up the cam surfaces 8 until they reach the dwells 9, further rotary movement of said finger portions being prevented by the stop projections 10. The movement of said finger portions up along said cam surfaces causes the locking member to be pulled downwardly against the tension of the 20 spring 30 so that said finger portions engage the cam surfaces with yielding effect and there is thus prevented undue wear of the gasket 32 with which the closure is usually provided, said gasket being interposed between the top flange 5 of the neck and the marginal portion 16 of the closure body member. The cam surfaces 8 of the neck, are of course, of such pitch or the recess 18 is of such depth that the upper end portion of the locking member does not leave the recess 18 of the body member 25 during connection of the closure to the neck so that there is no liability of undue separation of the closure body and locking members which would permit relative rotary movement therebetween.

30 To remove the closure from the neck, it is only necessary to turn the closure in a counter-clockwise direction which causes the finger portions thereof to leave the dwells 9 and ride down the cam surfaces 8 until they reach the passageways 7, whereupon the closure 35 can be readily lifted from the neck.

Due to the tubular construction of the connecting member 25, an ample air passage 35 is provided therethrough for venting to the 40 atmosphere the interior of the neck and hence the interior of member 1 when the closure is connected to the neck, so that the closure need not be provided with other openings for such purpose. Preferably, the lower end of the skirt portion 17 of the closure body member is bent inwardly beneath the gasket 32 so that 45 said gasket is always maintained against the marginal portion 16 thereof, as clearly indicated in Fig. 3.

50 In the modification shown in Figs. 7 and 8, the connecting member for the body and locking members of the closure is in the form of a cotter pin 36. The eye 37 of said pin at the lower end thereof not only serves as an efficient abutment for the lower end of spring 30

but also provides a means of connection for a chain or the like if it is desired to permanently attach the closure to the neck or to member 1. The upper ends 38 of the two legs of the pin are bent outwardly and may or may not be surrounded by a bead stuck up from the top wall of the dome portion 15 of the closure body member, an annular bead 39 being here shown. The two legs of the cotter pin are, of course, separated a sufficient amount to permit the interior of the neck and the interior of the member 1 to be freely vented to the atmosphere, as will be readily understood, or space is provided around said legs for venting purposes.

55 I claim—

1. A closure for tubular necks having opposed rigid cam portions, comprising a body member having a non-circular recess, a locking member having a non-circular portion fitting said recess and movable vertically therein without rotation, said locking member being also provided with opposed rigid locking portions adapted to be moved along the cam portions of a neck to effect detachable connection of the closure to said neck, said locking member moving downwardly relative to said body member during such movement along said cam portions, and yielding means effective upon both said body and locking members and normally resisting downward movement of said locking member relative to said body member, whereby the locking portions of said locking member engage said cam portions with yielding effect.

2. A closure for tubular necks having opposed rigid cam portions, comprising a body member having a non-circular recess, a locking member having a non-circular portion fitting said recess and movable vertically therein without rotation, said locking member being also provided with opposed rigid locking portions adapted to be moved along the cam portions of a neck to effect detachable connection of the closure to said neck, said locking member moving downwardly relative to said body portion during such movement along said cam portions, said body member being provided with an abutment spaced therefrom, and yielding means effective upon said locking member and said body member abutment and normally resisting downward movement of said locking member relative to said body member, whereby the locking portions of said locking member engage said cam portions with yielding effect.

3. A closure for tubular necks having opposed rigid cam portions, comprising a body member having a non-circular recess, a locking member having a non-circular portion fitting said recess and movable vertically therein without rotation, said locking member being also provided with opposed rigid locking portions adapted to be moved along the cam portions of a neck to effect detachable con-

- nection of the closure to said neck, said locking member moving downwardly relative to said body member during such movement along said cam portions, said body member 5 being provided with an abutment spaced therefrom and the non-circular portion of said locking member being arranged between said body member and the abutment thereof, and yielding means effective upon both said body 10 and locking members and normally resisting downward movement of said locking member relative to said body member, whereby the locking portions of said locking member engage said cam portions with yielding effect.
- 15 4. A closure for tubular necks having opposed rigid cam portions, comprising a body member having a non-circular recess, a locking member having a non-circular portion fitting said recess and movable vertically there- 20 in without rotation, said locking member being also provided with opposed rigid locking portions adapted to be moved along the cam portions of a neck to effect detachable connection of the closure to said neck, said locking member moving downwardly relative to said body member during such movement along said cam portions, said body member being provided with a depending part having an abutment at its lower end, and yielding 25 means effective upon said locking member and said abutment and normally resisting downward movement of said locking member relative to said body member, whereby the locking portions of said locking member engage said cam portions with yielding effect.
- 30 5. A closure for tubular necks having opposed rigid cam portions, comprising a body member having a non-circular recess, a locking member having a non-circular portion fitting said recess and movable vertically there- 35 in without rotation, said locking member being also provided with opposed rigid locking portions adapted to be moved along the cam portions of a neck to effect detachable connection of the closure to said neck, said locking member moving downwardly relative to said neck during such movement along said cam portions, said body member being provided with a depending part extending into said recess and having an abut- 40 ment at its lower end, and yielding means effective upon said locking member and said abutment and normally resisting downward movement of said locking member relative to said body member, whereby the locking portions of said locking member engage said cam portions with yielding effect.
- 45 6. A closure for tubular necks having opposed rigid cam portions, comprising a body member having a non-circular recess and abutments above and below the same, a locking member having a non-circular portion fitting said recess and movable vertically there- 50 in without rotation between said abutments, said locking member being also provided with opposed rigid locking portions adapted to be moved along the cam portions of a neck to effect detachable connection of the closure to said neck, said locking member moving downwardly toward said lower abut- 55 ment during connection of the closure to the neck, and yielding means effective upon said locking member and said lower abutment and normally resisting such downward movement of said locking member, whereby the locking portions of said locking member engage said cam portions with yielding effect.
- 60 7. A closure for tubular necks having opposed rigid cam portions, comprising a body member having a non-circular recess, a locking member having a non-circular portion fitting said recess and movable vertically there- 65 in without rotation, said locking member being also provided with opposed rigid locking portions adapted to be moved along the cam portions of a neck to effect detachable connection of the closure to said neck, said locking member moving downwardly relative to said body member during such movement along said cam portions, said body member being provided with a tubular depending part having an abutment at its lower end, and yielding means effective upon said locking member and said abutment and normally resisting downward movement of said locking member relative to said body member, whereby the locking portions of said locking member engage said cam portions with yielding effect.
- 80 8. A closure for tubular necks having opposed rigid cam portions, comprising a body member having a non-circular recess and abutments above and below the same, a locking member having a non-circular portion fitting said recess and movable vertically there- 85 in without rotation between said abutments, said locking member being also provided with opposed rigid locking portions adapted to be moved along the cam portions of a neck to effect detachable connection of the closure to said neck, said locking member moving downwardly toward said lower abut- 90 ment during connection of the closure to the neck, and yielding means effective upon said locking member and said lower abutment and normally resisting such downward movement of said locking member, whereby the locking portions of said locking member engage said cam portions with yielding effect.
- 95 9. A closure for tubular necks having opposed rigid cam portions, comprising a body member having a non-circular recess and abutments above and below the same, a locking member having a non-circular portion fitting said recess and movable vertically there- 100 in without rotation between said abutments, said locking member being also provided with opposed rigid locking portions adapted to be moved along the cam portions of a neck to effect detachable connection of the closure to said neck, said locking member moving downwardly toward said lower abut- 105 ment during connection of the closure to the neck, and yielding means effective upon said locking member and said lower abutment and normally resisting such downward movement of said locking member, whereby the locking portions of said locking member engage said cam portions with yielding effect.
- 110 10. A closure for tubular necks having opposed rigid cam portions, comprising a body member having a non-circular recess and abutments above and below the same, a locking member having a non-circular portion fitting said recess and movable vertically there- 115 in without rotation between said abutments, said locking member being also provided with opposed rigid locking portions adapted to be moved along the cam portions of a neck to effect detachable connection of the closure to said neck, said locking member moving downwardly toward said lower abut- 120 ment during connection of the closure to the neck, and yielding means effective upon said locking member and said lower abutment and normally resisting such downward movement of said locking member, whereby the locking portions of said locking member engage said cam portions with yielding effect.
- 125 11. A closure for tubular necks having opposed rigid cam portions, comprising a body member having a non-circular recess, a locking member having a non-circular portion fitting said recess and movable vertically there- 130 in without rotation, said locking member being also provided with opposed rigid locking portions adapted to be moved along the cam portions of a neck to effect detachable connection of the closure to said neck, said locking member moving downwardly relative to said body member during such movement along said cam portions, said body member being provided with a tubular depending part having an abutment at its lower end, and yielding means effective upon said locking member and said abutment and normally resisting downward movement of said locking member relative to said body member, whereby the locking portions of said locking member engage said cam portions with yielding effect.

In testimony whereof I hereby affix my signature.

CHARLES H. BELL.
